(57) **CLAIM**

The ornamental design for a UAV remote control mount adapter apparatus, as shown and described.

DESCRIPTION

FIG. 1 is a perspective view showing our new UAV remote control mount adapter apparatus design;

FIG. 2 is a lower perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is a right side view thereof, as engaged with an exemplary tripod and an exemplary UAV remote design. The broken lines shown are included only for the purpose of illustrating unclaimed portions of the article along with environmental subject matter, and form no part of the claimed design.
